UNITED STATES PATENT OFFICE.

WILLIAM J. BRITT, JR., OF ST. LOUIS, MISSOURI, ASSIGNOR TO KILLARK ELECTRIC MANUFACTURING COMPANY, OF ST. LOUIS, MISSOURI, A CORPORATION OF MISSOURI.

INCLOSED FUSE.

1,129,447.

Specification of Letters Patent. Patented Feb. 23, 1915.

Original application filed December 15, 1913, Serial No. 806,820. Divided and this application filed June 1, 1914. Serial No. 342,137.

To all whom it may concern:

Be it known that I, WILLIAM J. BRITT, Jr., a citizen of the United States, residing at the city of St. Louis, State of Missouri, have invented a certain new and useful Improvement in Inclosed Fuses, (being a division of my application for Letters Patent for fuses on which issued to me September 15, 1914, Patent No. 1,110,478,) of which the following is a specification, reference being had to the accompanying drawing, forming a part thereof, in which—

Figure 1 is an elevational view, partly in longitudinal section, of an inclosed fuse embodying my present invention; Fig. 2 is a similar view thereof taken approximately at right angles to the view shown in Fig. 1; Fig. 3 is a transverse sectional view on the lines 3—3, Figs. 1 and 2; and Fig. 4 is a perspective view of a member of the terminal or contact-blade and fusible link securing-means.

This invention relates generally to electric safety fuses and, more particularly, to a certain new and useful improvement in that class of electric safety fuses commonly known as inclosed or cartridge fuses. Fuses of this class usually comprise a hollow shell or casing of fibrous or other analogous insulation material, end-caps or closures, terminal members or contact-blades extending longitudinally of the casing and projecting therefrom at its ends through the end-caps, a suitable fusible element or link suitably electrically connected to the contact-blades and bridging the space therebetween within the casing, the fusible element or link having a current carrying-capacity less than the current carrying-capacity of the contact-blades and being adapted to carry the current up to a certain rated amperage and to blow or fuse on an overload or increase of current, thereby protecting the electric circuit in which the fuse may be arranged or inserted, as will be well understood, and a filling of suitable non-conducting material, preferably in a pulverulent or finely divided state, the function of which is to dissipate the heat and provide minute paths or interstices for the escape of the vapor or gases evolved upon the fusing or blowing of the fusible element. Heretofore, not

only have the blade-terminals and end-caps or closures of the casing been secured within and upon the casing in various ways and by various means, but also the fusible element or link has been usually soldered, riveted, or bolted directly to, and thereby fixed or held in electrical connection with, the terminal or contact-blades. The members or parts of fuses so constructed are, so far as I am aware, however, more or less difficult of assemblage and more or less expensive to manufacture.

The principal objects of my present invention are to provide an efficient fuse of the class stated of simple, economical, and inexpensive construction, of few readily assembled and renewable parts or members, and in which the terminal or contact-blades and fusible-element are conveniently secured not only renewably together in electrical contact, but also operatively to, and properly centered longitudinally within, the casing.

With the above and other objects in view, my present invention resides in the provision in a fuse of the kind stated of means adapted not only to renewably secure the blade-terminals and fusible-element together in electrical-contact or connection, but also to operatively and removably secure the blade-terminals with their so connected fusible element to, and at the same time properly center the same longitudinally within, the casing, and in certain novel features of form, construction, arrangement, and combination of parts, all as will hereinafter be described and afterward pointed out in the claims.

Referring to the accompanying drawings, in which like reference characters refer to like parts throughout the several views, 1 indicates the fuse casing, which is preferably an open-ended tubular shell of fibrous or other analogous insulation material and which may be of any suitable length and diameter as required according to the desired size or current-carrying capacity of the fuse.

2—2 indicate suitable flanged or cup-shaped preferably metallic caps which are adapted, in the finished fuse, to fit on casing 1 at its opposite ends and provide closures

therefor, caps 2—2 being removably secured on casing 1 by means of small screws or other like fastening means 3.

The fusible element or link of the fuse, which extends lengthwise of, and within casing 1, preferably comprises a plurality of members 4—4 in the form of relatively broad flat strips of zinc or other suitable readily fusible metal electrically connected and fastened together at their opposite inner ends by a plurality of separated wires 5 also of zinc or other suitable readily fusible metal, fusible or link-members 4—4 being adapted, as shown, to fit flatwise upon the inner ends of oppositely-disposed relatively thick, heavy, preferably flat fuse terminal-members or contact-blades 6—6 of copper or other suitable conducting material, which also extend lengthwise of casing 1 and at their outer ends project outwardly in the finished fuse through suitable elongated or rectangular slots in the face of end caps 2—2 and thereby form or provide contact-terminals for the fuse, each of the link members 4—4 being provided with a transverse perforation, as at 7, adapted, for purposes hereinafter appearing, to register with a corresponding transverse perforation, as at 8, in the respective blades 6.

Adjacent each of its ends, casing 1 is provided with a pair of diametrically opposite or alining openings or perforations, as at 1^a, preferably at right angles to the openings provided for cap-securing screws 3; and since the means for renewably securing the respective blades 6—6 and link-members 4—4 not only electrically together, but also in proper operative removable position to, and longitudinally centered within, casing 1, are duplicated at the opposite ends of the casing, merely one of said means will be now here described.

Extending transversely of casing 1 and loosely, that is to say, removably, through said registering perforations 8 and 7, and thereby engaging with blade 6 and link-member 4, is a pin 9 provided preferably integrally with an enlarged preferably cylindrical head 10 adapted at one end to tightly, but removably, fit in one of said alining openings 1^a, and thereby engage with casing 1, and at its other end to impingingly bear upon or engage with one of the broad flat faces of blade 6, as clearly seen in Figs. 1 and 3. At its other or reduced end, pin 9 is threaded, as at 11, to receive an internally threaded tubular member or nut 12 having a length approximately equal to the length of head 10 and being similarly adapted at one end to tightly, but removably, fit in opposite opening 1^a, and thereby engage with casing 1, and at its other or inner end to impingingly bear upon or engage with the upper

or outer flat face of link-member 4, as also seen clearly in Figs. 1 and 3, whereby it will be evident, head 10 and member or nut 12 tightly impinging upon link-member 4 and blade 6, not only are blade 6 and link-member 4 tightly held in renewable electrical contact or connection, but also firmly, but removably, secured to, and at the same time properly centered longitudinally within, casing 1. Head 10 and nut or tubular member 11 being approximately flush at their outer or slotted faces with the periphery of casing 1, and the flanges of caps 2—2 being of sufficient length to extend inwardly beyond said openings 1^a, as seen clearly in Fig. 1, it will be evident not only that said openings 1^a will be completely covered, but also that said pin 9 with its head 10 and nut 12 will be firmly and positively held against removal in their described blade and link-securing position.

Surrounding the fusible element or link formed preferably, as stated, of said flat members 4 and wires 5 and filling the interior of casing 1, is a filling 13 of any suitable non-conducting material preferably in a pulverulent or finely divided state, such as pulverized plaster of Paris, marble, or slaked lime, adapted to dissipate the heat and provide minute paths or interstices for the escape of the vapor or gases arising or evolved upon the fusing or blowing of the fusible element or link, caps 2—2, which are, as is usual, preferably provided with suitable vent perforations or openings 14—14, being firmly held by screws 3 upon casing 1 and prevented thereby from being blown off casing 1 by the expansion of the gases generated on the fusing of said link.

In assembling the parts or members of my new fuse, blades 6—6 and fusible-members 4—4 with wires 5 electrically connected or fixed thereto are lengthwise slidably inserted into casing 1. Blades 6—6 and link-members 4—4 being now preferably held by means of the fingers or other suitable temporary means in flatwise engagement with their respective perforations 8 and 7 in registration, pins 9 are fitted from one side transversely of casing 1 through said registering perforations until their heads 10 engage at their inner ends or faces with blades 6—6, the outer ends or slotted faces of heads 10 being approximately flush with the periphery of casing 1. Centering members or nuts 12 are now threaded upon pins 9 to impingingly secure fusible-members 4 and blades 6—6 together in renewable surface contact and to also firmly secure blades 6—6 and the fusible link in operative longitudinally centered position within the casing 1, the outer ends or slotted faces of members or nuts 12 being also approximately flush with the periphery of casing 1. Filling 13 and end caps 2—2 are now, as de-

scribed, operatively placed within and secured upon casing 1, when the fuse is ready for marketing. It will be observed that caps 2—2, in addition to holding the blade-securing means in relatively fixed position, also prevent any pivotal or sidewise movement of blades 6—6 relatively to casing 1. To renew or replace any part or member of the fuse, it is merely necessary to remove end caps 2—2, when the remaining members of the fuse may be readily taken from casing 1, as will be obvious.

My new fuse may be economically manufactured, and it will be observed that the several parts thereof may be readily assembled and may also be easily and conveniently renewed or replaced. It is to be understood that the fusible element might, if desired, be duplicated, and at the same time 25 electrically connected to blades 6—6, on the opposite flat faces of blades 6—6 and that changes in the form, construction, arrangement, and combination of the several parts of the fuse may, within the scope of the appended claims, be made and substituted for those herein shown and described without departing from the nature and principle of my invention.

Having thus described my invention, what 30 I claim and desire to secure by Letters Patent is:

1. In a fuse of the class described, a tubular casing provided adjacent its end with a pair of diametrically opposite openings, a 35 terminal-blade having relatively broad flat opposite faces, said blade being transversely provided with a perforation at right angles to the said faces thereof, a flat fusible member adapted to fit flatwise upon said terminal-blade, said fusible member being also 40 transversely provided with a perforation adapted to register with said blade-perforation, and means adapted to secure said blade and fusible-member electrically together and 45 operatively to and within said casing, said means including a pin extending transversely of the casing through said registering perforations and projecting into said openings, and members on said pin impinging 50 engaging with said blade and fusible-member; substantially as described.

2. In a fuse of the class described, a tubular casing provided adjacent its end with a pair of diametrically opposite openings, a 55 terminal-blade having relatively broad flat opposite faces, said blade being transversely provided with a perforation at right angles to the said faces thereof, a flat fusible member adapted to fit flatwise upon said terminal-blade, said fusible member being also 60 transversely provided with a perforation adapted to register with said blade-perforation, and means adapted to secure said blade and fusible-member electrically together and 65 operatively to and within said casing, said

means including a pin extending transversely of the casing through said registering perforations, and members on said pin impinging engaging with said blade and fusible-member and projecting into said openings; substantially as described. 70

3. In a fuse of the class described, a tubular casing provided adjacent its end with a pair of diametrically opposite openings, a terminal-blade having relatively broad flat 75 opposite faces, said blade being transversely provided with a perforation at right angles to the said faces thereof, a flat fusible member adapted to fit flatwise upon said terminal-blade, said fusible-member being also 80 transversely provided with a perforation adapted to register with said blade-perforation, and means adapted to secure said blade and fusible-member electrically together and 85 operatively to and within said casing, said means including a pin extending transversely of the casing through said registering perforations, a head integral with said pin, and a nut having threaded engagement with said pin, said head and nut impinging engaging with said blade and fusible-member and 90 projecting into said openings; substantially as described.

4. In a fuse of the class described, a tubular casing provided adjacent its end with a 95 pair of diametrically opposite openings, a terminal-blade having relatively broad flat opposite faces, said blade being transversely provided with a perforation at right angles to the said faces thereof, a flat fusible-member 100 adapted to fit flatwise upon said terminal-blade, said fusible-member being also transversely provided with a perforation adapted to register with said blade-perforation, means adapted to removably secure 105 said blade and fusible member electrically together and operatively to and within said casing, said means including a pin extending transversely of the casing and loosely through said registering perforations, a 110 head integral with said pin, and a nut having threaded engagement with said pin, said head and nut impinging engaging with said blade and fusible-member and projecting removably into said openings, and means 115 on the casing for removably holding said securing-means in operative position; substantially as described.

5. In a fuse of the class described, a tubular casing provided adjacent its end with a 120 pair of diametrically opposite openings, a terminal-blade having relatively broad flat opposite faces, said blade being transversely provided with a perforation at right angles to the said faces thereof, a flat fusible member 125 adapted to fit flatwise upon said terminal-blade, said fusible-member being also transversely provided with a perforation adapted to register with said blade-perforation, means adapted to removably secure 130

said blade and fusible-member electrically together and operatively to and within said casing, said means including a pin extending transversely of the casing and loosely 5 through said registering perforations, a head integral with said pin, and a nut having threaded engagement with said pin, said head and nut impingingly engaging with said blade and fusible-member and projecting 10 removably into said openings, and a

flanged end-cap on said casing for removably holding said securing-means in operative position; substantially as described.

In testimony whereof, I have signed my name to this specification, in the presence of 15 two subscribing witnesses.

WILLIAM J. BRITT, JR.
